MULTIPLE ANVIL FOR FASTENER SETTING MACHINES

Arthur R. Havener, Wayland, Mass., assignor to Judson L. Thomson Manufacturing Company, Waltham, Mass., a corporation of Massachusetts

Application March 21, 1939, Serial No. 263,143

9 Claims. (Cl. 218—0.5)

This invention relates to multiple anvils for fastener setting machines such as riveting, eyeleting and similar machines, and more particularly to anvils of this character which are self-adjusting for different thicknesses of work.

In fastener setting machines of the character described which employ multiple anvils for setting two or more rivets, eyelets or fasteners simultaneously, it has been customary to mount the anvils in a common support and to adjust and fasten each anvil separately therein. Not only are such adjustments somewhat difficult to make exactly uniform for work of uniform thickness, but they do not allow for any variation in thickness of the work, and, when this occurs, the fasteners in each group set simultaneously will be set in differing degrees of tightness. When the work consists in fastening separate pieces together, a variation in thickness will result in defective work because the fasteners in the thinner portions of the work will be loose.

The main object of my invention is the provision in machines of the character described, of multiple anvils which, after adjustment for the particular work to be performed, are capable of self-adjustment to take care of inequalities of thickness in the work.

My invention in its preferred embodiment employs a plurality of anvils mounted for free vertical movement through suitable bores in a fixed plate and backed up by an oscillatory member adapted to equalize the pressure exerted on the anvils by the setting members during the setting of the rivets or other fasteners. The backing member is of such form and so mounted that undue pressure upon one of two or more anvils causes it to shift in position until the pressures of all the anvils upon it are equalized.

The backing member may be made in various forms to conform to the number and arrangement of the anvils. When two anvils are used, the backing member may be pivotally mounted to oscillate so that the pressure upon the two anvils will be equalized by the oscillation of the backing member to compensate for the variation in the thickness of the material. For a group of three anvils, the backing member may be made of semi-spherical shape mounted in a suitably formed recess, capable of tilting in all directions to bring about an equalization of pressure upon the three anvils. When more than three anvils are grouped, one or the other of these forms may be used, dependent upon the arrangement of the anvils.

In the accompanying drawing illustrating two forms of my invention,

Figure 1 is a side elevation of one form of multiple anvil comprising two anvils constructed and adapted to be operated in accordance with my invention.

Figure 2 is a vertical, sectional view on line 2—2 in Figure 1.

Figure 3 is a top plan view of the same.

Figure 4 is a side elevation of the upper portion of the two-anvil form with another form 5 of equalizing member.

Figure 5 is a vertical, sectional view of the same on line 5—5 in Figure 4.

Figure 6 is a plan view of the same.

Figure 7 is a side elevation of the upper portion of a three-anvil form of the invention with another form of equalizing member.

Figure 8 is a vertical, sectional view on line 8—8 of Figure 7.

Figure 9 is a plan view of the same.

Referring first to the construction shown in Figures 1 to 3, at 1 is indicated a bracket fixed to the machine, for supporting the anvils. At its outer end it is provided with a vertical bore 2 which receives a bushing 3 and within this bushing is vertically movable a shank 4. This shank is threaded at 5 adjacent to its upper end and engaging therewith is an adjusting nut 6, the lower edge of which bears on the upper edge of the bushing 3. By turning this nut 6 the shank 4 may be adjusted heightwise. At its upper end this shank 4 has secured thereto a multiple anvil support 7 and this is held from rotation about the axis of the shank 4 by a rearward extension 8 which is perforated and carries a bushing 9 for sliding engagement with a guide post 10 secured at its lower end in the bracket 1. The support 7 is provided with a base 11 and upstanding spaced side wall members 12 bridged over at their upper ends by a cover member 13. Between the sides 12 there is pivotally supported on a pivot pin 14 a backing equalizing member 15. This equalizing member is provided with a pair of spaced rounded projections 16 on which are supported the bottom ends of a pair of anvils 17 which are vertically slidable through bushings 18 in bores in a circular boss 19 integral with and upstanding from the top face of the cover member 13. As shown these anvils have the usual spring pressed pilots 20 for receiving tubular rivets, although it is evident that they might be otherwise formed, depending upon the particular type of fastening which it is desired to set. As shown, the equalizer 15 may have its extent of rocking motion determined as by a pair of abutment screws 21 threaded through the cover plate 13 above opposite extremities of the equalizer 15. It will be evident that within the limits of rocking permitted by adjustment of these abutment screws 21, greater pressure exerted downwardly against one of the anvils 17 will cause a lifting of the other through rocking of the equalizer, thus to equalize the pressure exerted on the two anvils, so as to take care of differences in thickness of

the work and differences in dimensions of the upper tools which cooperate with the anvils in setting the fasteners. These abutment screws 21 may be fixed in adjusted positions as by means 5 of the set screws 22. It will be evident from this construction that if desired either of the setting tools may be adjusted normally higher than the other and if desired they may be locked in such relative positions without capability of 10 rocking of the equalizer.

In Figures 4, 5 and 6 a modified construction is shown also intended for use with a pair of anvils. In this modification the upper end of the shank 4a is shown as extended into a casing 15 member 30 having spaced upwardly extending side portions 31. The top face of the shank member 4a is provided with a semi-cylindrical slot 32 within which is rockably mounted the equalizing backing member 33. This equalizer 20 is shown as of generally semi-cylindrical contour with a pair of rounded projections 34 on its upper otherwise flat face. These projections 34 are positioned to support the anvils 17 which are mounted for sliding motion through bushings 35 seated in through and through bores in the cover plate 36, this cover plate bridging the side walls 31 and being secured thereto as by the screws 37 passing through holes in the corners of the cover plate 36 and threaded into the side wall members 31. To prevent turning of the casing 30 and the shank 4, the casing 30 may be slidably guided on the post 10 as shown in Figure 2, the casing being secured to the shank as by a set screw 38.

35 In Figures 7, 8 and 9 a construction is shown suitable for more than two anvils, three anvils being shown. In this construction the upper end of the stem 4 is shown as provided with a socket 40 within which is rockably mounted a hemispherical equalizer 41, the upper face of which is provided with the rounded projections 42 against which engage the lower ends of the anvils 17. As these anvils are shown arranged in triangular grouping about a central vertical axis, the projections 45 42 on the equalizer are similarly arranged. As the equalizer or backing member may tilt in any direction, being universally mounted, the pressure is equalized between all three of the anvils. The casing 43 which houses the equalizer 41 may be identical in construction with that shown in Figures 4, 5 and 6, except that its cover 44 will have three bushed openings to receive the three anvils 17. It may be secured to the stem 4b as by a set screw 45 55 in the same manner that the casing 30 is secured to the stem 4a in the construction of Figures 4 to 6.

From the foregoing description of certain embodiments of this invention, it will be evident to those skilled in the art that various changes and modifications might be made without departing from the spirit or scope of this invention as defined by the appended claims.

I claim:

60 1. An anvil of the character described comprising a support, a plurality of anvils mounted in said support for free longitudinal movement, and a backing member mounted in said support for engagement with the bottom ends of said 65 anvils and for oscillation to equalize the pressure on said anvils during a setting operation.

2. An anvil of the character described comprising a support, a plurality of parallel anvils mounted in said support for free longitudinal movement, and an oscillatory member mounted in said support in engagement with the back ends 5 of said anvils for equalizing the pressure thereon during a setting operation.

3. An anvil of the character described comprising a support, a plurality of parallel anvils mounted in said support in close proximity to 10 each other and longitudinally movable therein, and an oscillatory member mounted in said support for engaging the bottom ends of said anvils for equalizing the pressure thereon during a setting operation.

4. An anvil of the character described comprising a support provided with a plurality of parallel bores open at both ends, an anvil mounted in each of said bores and longitudinally movable therein, and an oscillatory member mounted in said support for engaging the bottom ends 20 of said anvils for equalizing the pressure thereon during a setting operation.

5. An anvil of the character described comprising a support, a pair of anvils mounted in 25 said support for longitudinal movement therein, and an oscillatory member pivotally mounted in said support for engaging the bottom ends of said anvils for equalizing the pressure thereon during a setting operation.

6. An anvil of the character described comprising a support, three parallel anvils mounted in said support for longitudinal movement therein, and an oscillatory member of semispherical 30 form mounted for free tilting movement and having its diametrical face engaging the bottom ends of all said anvils for equalizing the pressure thereon during a setting operation.

7. An anvil of the character described comprising a plate provided with a plurality of 35 through and through bores, an anvil longitudinally movable in each of said bores, an oscillatory member mounted below said plate for engaging the bottom ends of said anvils for equalizing the pressure exerted on said anvils during a setting operation, and means for limiting the amplitude of oscillation of said member.

8. An anvil of the character described comprising a plate provided with a plurality of 40 parallel vertical through and through bores, an anvil slidably mounted in each of said bores, and a backing member mounted below said plate and having an approximately horizontal top face for supporting said anvils in said bores, said member being mounted for a tilting movement for equalizing the pressure exerted on said anvils during a setting operation.

9. An anvil of the character described comprising a plate provided with a plurality of parallel vertical through and through bores, an 45 anvil slidably mounted in each of said bores, and a backing member mounted below said plate and having an approximately horizontal top face for supporting said anvils in said bores, said member being mounted for a tilting movement for equalizing the pressure exerted on said anvils during a setting operation, said top face being provided with rounded projections on which the bottoms of said anvils directly engage.

ARTHUR R. HAVENER. 70
